UNITED STATES PATENT OFFICE.

FREDERICK C. OVERBURY, OF HILLSDALE, NEW JERSEY, ASSIGNOR TO THE FLINTKOTE COMPANY, OF BOSTON, MASSACHUSETTS, A CORPORATION OF MASSACHUSETTS.

METHOD AND APPARATUS FOR MAKING PREPARED ROOFING ELEMENTS.

1,314,476.

Specification of Letters Patent. Patented Aug. 26, 1919.

Application filed December 28, 1917. Serial No. 209,228.

To all whom it may concern:

Be it known that I, FREDERICK C. OVERBURY, a citizen of the United States, residing at Hillsdale, in the county of Bergen 5 and State of New Jersey, have invented new and useful Improvements in Methods and Apparatus for Making Prepared Roofing Elements, of which the following is a specification.

10 This invention has relation to the manufacture of prepared roofing elements in the form of "shingle strips," so-called, which consist of slabs or strips having spaced tabs or projections which are exposed when the 15 strips are laid in overlapping rows, and present the appearance of shingles, tiles or slates. Such prepared roofing consists of a foundation of fibrous material, usually rag felt, which is porous and absorbent, and 20 which is saturated or impregnated with a relatively low-melting-point asphalt or other hydrocarbon to waterproof the sheet, and coated with a layer of relatively high-melting-point pitch or asphalt, in which is 25 partially embedded a surfacing material such as grit made of crushed or flaked tile, slate, granite or other mineral to give to the roofing an ornamental appearance, in addition to increasing its capacity to withstand 30 the action of the elements and increasing its fireproof and acidproof qualities.

Heretofore it has been the practice first to produce a sheet of roofing such as described, and then, by means of cutting 35 machines, to divide the sheet into shingle strips such as described. This has been done ordinarily as described in my Patent No. 908,125, by forming the sheet with a series of transverse slots and then slitting it longitudinally, or else by severing the sheet transversely into shingle strips as described in my Patent No. 1,182,416. While such a method of producing shingle strips has been commercially successful, yet certain difficulties have presented themselves which militate against an economical and rapid production of the strips.

Saturated, coated, mineral-surfaced roofing is difficult to cut because the grit wears out the knives very rapidly, especially those which are employed for cutting the slots in the sheets, and because of the character of the saturating and coating compounds which causes them to clog the dies or cutters, especially when mixed with grit. The waste

pieces, which are formed in cutting the slots in the sheet, contain much valuable compound, grit and fiber, but, because of the mixture of the grit with the saturating and coating compound, it is difficult to reclaim 60 the several constituents without the expenditure of an undue amount of money.

The present invention has for its object to remedy and overcome the faults and difficulties which have heretofore inured to the 65 method of manufacture hereinbefore briefly described. This is accomplished, according to the present invention, by forming the slots in the sheet of felt before it is saturated or coated. The waste cuttings may therefore be utilized in the beaters in the 70 manufacture of felt without any other treatment. In this way, the slotting is accomplished without permitting the slotting knives to come into contact either with the saturating 75 compound, the coating compound or the grit. A further result is secured in that the coating covers the cut edges or walls of the slots, increases to some extent the thickness thereof by coating the adjacent margins of 80 the under side of the sheet, and enables the walls of the slots to be surfaced with the grit.

Referring to the accompanying drawings, 85

Figure 1 represents conventionally an apparatus or instrumentality which may be employed for the practice of my invention.

Fig. 2 illustrates a sheet during the course 90 of its manufacture into shingle strips.

Fig. 3 illustrates how the slots may be formed longitudinally in the sheet instead of transversely thereof.

Fig. 4 illustrates a staggered arrangement 95 of slots in the sheet.

So far as the details of manufacture are concerned, in the practice of my invention, it is quite immaterial whether the resultant shingle strips are cut crosswise of the sheet as illustrated in my Patent No. 1,150,298, 100 dated August 17, 1915, or whether they are cut lengthwise of the sheet as shown in my Patent No. 908,125, dated December 29, 1908. In either case, the slotting is accomplished before the saturating and the coating compounds and the surfacing grit are applied to the sheet.

Referring to the drawing,—the sheet of 110 felt or other equivalent of porous, absorbent, fibrous material is shown as being drawn

from a roll 10 to a slotting machine which is indicated as a whole at 11. Said machine is provided with the feed rolls 12, 12, and with the slotting rolls which are indicated 5 at 13, 14. These rolls may be formed substantially as illustrated in the patent to Perry G. Gardner No. 1,191,297, dated July 18, 1916, for cutting a plurality of transverse slots *b* in the sheet *a*, as indicated in Fig. 2; 10 or the dies and recesses may be arranged to cut a plurality of transverse rows of longitudinal slots as indicated at *c* in Fig. 3. If desired, however, the slotting rolls may be formed to cut slots *d d'* which are staggered 15 as shown in Fig. 4. The slots *b* and the slots *d d'* are the equivalents of each other, and, on slitting the sheet in either case, two strips are formed each of which is provided with a plurality of tabs or projections. The 20 cuttings or waste pieces in the machine 11 are deflected by a chute 15 into a receptacle or basket 16.

After having been slotted, the sheet is now carried through a tank 17 containing a 25 saturating compound of relatively low-melting-point asphalt or other suitable hydrocarbon material which is kept in liquid condition by any suitable heating means such as a steam coil 18. The sheet is caused 30 to travel through the bath of molten hydrocarbon, and, on emerging therefrom, passes between squeeze rolls 19 by which the excess or surplus compound is pressed from the sheet, leaving it comparatively dry. There- 35 after the sheet is carried through a suitable cooling or refrigerating apparatus, indicated as a whole at 20 and illustrated as comprising two pairs of rolls 21, 21, 22, 22, which are supplied with a cooling or refrigerating 40 medium for chilling the sheet to the desirable lower temperature. If desired, assuming that the slots are either as indicated at *b* in Fig. 2 or as at *d d'* in Fig. 4, the sheet 45 may be now severed by a longitudinal cut, and I have illustrated at 23 a machine by which this may be accomplished. The said machine is provided with the feed rolls 24, 24, and with two rotary cutter blades 125, 125, for splitting the sheet longitudinally as 50 indicated at *e* in Fig. 2. The rolls 24, 24, may be formed in sections and set at a slight angle so as to cause the two halves of the sheet to be spread slightly and thereby separate the cut edges, although this is not essential. 55 The sheet is now coated with a relatively high-melting-point pitch or asphalt, and to this end it is fed to a machine comprising two rolls 25, 25, which are preferably steam-heated and which are carefully adjusted to 60 a proper distance from each other. The asphalt is delivered to the top of the sheet by a pipe 26 and is spread to the desired thickness upon the sheet as the latter passes between the rolls. To prevent the asphalt from dropping through the slots in the sheet, the latter may be passed over a stationary plate or table 27. Any surplus asphalt that is left upon the lower roll 25 may be scraped therefrom by a scraper 28 and delivered to a heated tank 29. The sheet is now ready to 70 be coated with grit and it is consequently passed beneath a hopper or trough 30 containing grit of the desired color, from which the grit is delivered in a thin stream upon the top of the coated sheet, and, since the 75 coating is still plastic, the grit adheres thereto to the desired extent. Any grit falling through the slots in the sheet is caught by a receptacle 31, a chute 32 being employed to deflect the grit into the receptacle if found 80 to be desirable. The sheet is now passed over a roll 33 and under a roll 34, so that the surplus or excess grit may be delivered to a receptacle 35. After passing under a roll 36, the sheet finally reaches pressure rolls 37, 37, 85 which partially embed the adhering grit into the body of the coating on the sheet. The sheet should now be cooled and any suitable cooling instrumentalities may be employed. I have conventionally illustrated at 38 a 90 festooning mechanism for cooling the sheet prior to its delivery to the chopping machine by which the individual shingle strips are cut from the sheet. The machine, as conventionally illustrated, is provided with feed 95 rolls 39 and a cutting mechanism comprising a stationary shear blade 40 and a rotating associated cutter or chopper 41. Where the sheet is formed as illustrated in Fig. 2, the cutter 41 is arranged to cut the sheet trans- 100 versely on a line which is indicated at *h h* in Fig. 2, so as to form two shingle strips *i i* of the same length and breadth, and each having along one longitudinal edge a plurality of spaced tabs or projections. If the 105 slots be formed in the sheet as indicated in Fig. 3, the cutter 41 may be rotated to cut the sheet transversely on the lines *j j* and *k k*, one cut being intermediate the ends of two adjacent rows of slots and the other be- 110 ing intermediate of the ends of the slots of each row. If the slot be staggered as shown in Fig. 4, the cutter 41 is arranged in two parts so as to make the cuts indicated at *m m* and *n n*, this being facilitated by the 115 previous longitudinal slitting of the sheet. I do not, of course, intend to limit the invention to the formation of the slots in any particular way, the invention residing more especially in the formation of slots in the 120 sheet prior to its being saturated and coated. Care should be taken in the practice of the method herein described to see that the various rolls in the several instrumentalities be- 125 tween the roll of felt 10 and the pressure rolls 37, are synchronized as to their peripheral speed so that the sheet may be fed through the several instrumentalities without danger of being torn or split. The slots should be so formed that, when it is finally severed 130

into strips, the slots constitute the recesses between the several tabs or projections. These slots may, for example, be one-half an inch in width and of such length as to provide tabs which are about four and one-half to five inches in length.

By first slotting the sheet, it will be noted that I effect a very material saving in the quantities of saturating compound, coating compound and the grit which are used in the manufacture of the shingle strips, and I also effect a saving in the felt, because the cuttings of the raw felt may be reused in the manufacture of more felt. Another result which I secure is that the walls of the slots are covered with the coating compound and are also covered with the grit, and usually the coating compound works to some extent under the margins of the sheet on its under side adjacent the slots so as to increase the thickness of the sheet at the edges of the slots. Where the sheet is split longitudinally before being coated, as indicated in Figs. 1 and 2, those edges, which subsequently become the lower edges of the tabs on the shingle strips, are also coated with the coating compound and faced with the grit.

What I claim is:

1. The method of making shingle strips, which includes first forming slots in a sheet of felt, then saturating the felt with a hydrocarbon compound, and subsequently cutting the sheet in such relation to the slots as to form shingle strips with slots or projections.

2. The method of making shingle strips, which consists in forming in a sheet of raw felt those slots which constitute the recesses between the tabs or projections of the completed shingle strips, saturating and coating the slotted sheet, and cutting said sheet into shingle strips.

3. The method of making shingle strips, which consists in forming in a sheet of raw felt those slots which constitute the recesses between the tabs or projections of the completed shingle strips, saturating and coating the slotted sheet, supplying a facing of grit to the coated sheet, and severing said sheet transversely into shingle strips.

4. The method of making shingle strips, which consists in forming regularly spaced slots in a sheet of raw felt, passing such slotted sheet through a bath of hydrocarbon, coating the saturated sheet with asphalt or pitch, supplying a facing of grit to the coat-

ing, and cutting said sheets into shingle strips in which the slots form recesses between the tabs or projections thereof.

5. The method of making shingle strips, which consists in forming a longitudinal row of transverse slots in a sheet of raw felt, slitting said sheet between the outer ends of the slots, saturating and coating said sheet with waterproofing and weatherproofing compounds, applying grit to the coated sheet, and transversely severing said sheet into shingle strips.

6. In combination, the following instrumentalities arranged in the order named, to wit: mechanism for forming a plurality of slots in a sheet of felt, means for saturating said slotted sheet, and means for cutting said sheet into a plurality of shingle strips in which said slots provide tabs or projections.

7. In combination, the following instrumentalities arranged in the order named, to wit: mechanism for forming a plurality of slots in a sheet of felt, means for saturating said slotted sheet, means for coating said sheet with a waterproof compound, and means for cutting said sheet into a plurality of shingle strips in which said slots provide tabs or projections.

8. In combination, the following instrumentalities arranged in the order named, to wit: mechanism for forming a plurality of slots in a sheet of felt, means for saturating said slotted sheet, means for coating said sheet with a waterproof compound, means for applying a layer of grit on the coated surface of said sheet, and means for cutting said sheet into a plurality of shingle strips in which said slots provide tabs or projections.

9. In combination, the following instrumentalities arranged in the order named to wit: mechanism for forming a longitudinal row of transverse slots in a sheet of felt, means for saturating said sheet with a waterproof hydrocarbon compound, means for slitting said sheet longitudinally along a line intersecting said slots, means for applying a plastic coating to the slitted sheet, means for applying a layer of grit to said coating, and means for transversely severing said slitted sheet into shingle strips.

In testimony whereof I have affixed my signature.

FREDERICK C. OVERBURY.
